R. G. SPEER.

HOT AIR HEATING SYSTEM.

APPLICATION FILED DEC. 23, 1907.

921,019.

Patented May 11, 1909.

UNITED STATES PATENT OFFICE

ROBERT G. SPEER, OF ST. LOUIS, MISSOURI, ASSIGNOR TO SARAH B. SPEER, OF ST. LOUIS, MISSOURI.

HOT-AIR HEATING SYSTEM.

No. 921,019.

Specification of Letters Patent. Patented May 11, 1909.

Application filed December 23, 1907. Serial No. 407,635.

To all whom it may concern:

Be it known that I, ROBERT G. SPEER, a citizen of the United States of America, and a resident of St. Louis, in the State of Missouri, have invented certain new and useful Improvements in Hot-Air Heating Systems, of which the following is a specification.

This invention relates to hot air heating systems for buildings, and has for its object to provide a simple and efficient structural arrangement and combination of parts, whereby great fuel economy is attained in the operation of the system, all as will hereinafter more fully appear.

In the accompanying drawings illustrative of the present invention: Figure 1, is a vertical sectional elevation. Fig. 2, is a detail transverse section on line 2—2 Fig. 1. Fig. 3, is a detail plan of one of the air feeding 20 heads of the fire chamber.

Similar numerals of reference indicate like parts in the different views.

Referring to the drawings, 1 represents the closed outer casing; 2 the fire pot, and 3 the 25 combustion chamber of a hot air furnace; the parts being constructed and arranged in any usual manner common to such type of furnaces.

4 is an inlet duct connecting with the lower 30 portion of the chamber formed by the casing 1 and adapted to introduce thereto the supply of air to be heated.

5 are one or more outlet ducts connecting with the upper portion of the chamber 35 formed by the casing 1 and adapted to conduct therefrom the heated air to the series of pipes or flues by which such heated air is conducted to the different points in the building.

6 is an outlet pipe connected to the upper 40 portion of the combustion chamber and adapted to conduct the heated products of combustion away from the same in manner hereinafter more particularly specified.

The construction so far described is common to any ordinary type of hot air furnaces, and a material part of the present invention involves in connection therewith a preheating attachment for the incoming supply of air, as follows:

50 7 is an air supply pipe extending from the exterior of the building and adapted to introduce a supply of outside atmospheric air.

Such pipe is provided with a vertical branch 8 connecting with any suitable portion of the interior of the building and adapted to take 55 a supply of air therefrom, and with a view to regulate the supply of air from the two sources, a valve 9, adapted to control the supply from either source, is arranged within the pipe 7, at the point of junction of the 60 pipe 7 and branch 8, and as illustrated in Fig. 1.

10 is a closed casing of any desired form, arranged between the aforesaid supply pipe 7 and the inlet duct 4 and having communication with both as shown.

11 is a secondary closed casing, preferably of a form corresponding to that of the casing 10, and arranged therein in a central manner, so as to provide an annular space or 70 passage between the two casings, and which space or passage communicates with the aforesaid inlet pipe 7 and inlet duct 4 respectively, to form a connection between the same.

12 is a branch or inlet pipe connecting at one end with the aforesaid outlet pipe 6 of the combustion chamber, and at the other end with the interior of the secondary casing 11, at one end of the same as shown in Fig. 1. 80

13 is a companion branch or outlet pipe also connecting at one end with the aforesaid outlet pipe 6 of the combustion chamber, and at the other end with the interior of the secondary casing 11, at the end of the same opposite to that at which the branch or inlet pipe 12 is connected.

14, is a branch pipe connecting with the outlet pipe 6 of the combustion chamber at a point between the connection of the aforesaid branches 12 and 13 thereto. Such branch pipe 14 extends to and is connected to the chimney of the building or like point of exhaust for the waste products of combustion.

15 is a valve or damper arranged in the aforesaid outlet pipe 6, at a point between the points of attachment of the branches 12 and 14 to such outlet pipe 6. The arrangement is such that with a closing of such 100 damper the heated products of combustion are directed down through the branch pipe 12, thence through the secondary chamber 11, and through the branch pipes 13 and 14.

to the place of exhaust; and in the passage through said secondary chamber the heated products of combustion effect a very thorough preheating of the supply of air intended for warming purposes and in a very economical manner. With the damper 15 open the products of combustion pass directly to the point of exhaust, with an attainment of no such preheating effects; such provision is however required in starting up the system, as well as in other temporary conditions requiring a maximum result from the system regardless of economy of fuel.

16 are a series of baffle plates arranged in spaced and transverse relation in the secondary casing 11 and which are adapted to convert the inner space of such casing into a serpentine or elongated passage adapted for a more effective radiation of the heat therefrom in the operation of the system.

17 are lateral passageways communicating with the secondary casing 11 near its lower part and between the series of baffle plates 16 aforesaid, and through which solid particles deposited by the passing products of combustion are conveniently removed at stated intervals.

18 are closure caps for the lateral passageways 17, and which caps are in place during the normal operation of the system.

19 is an inclined deflector arranged in the combustion chamber 3, immediately above the fire pot 2, and formed of fire clay or other suitable material, and which may be solid or perforated as desired. The heated products of combustion as they rise from the fuel are adapted to heat said deflector, which in turn is adapted to effect a very perfect combustion of such products as they pass along and over the top of said deflector in their passage to the outlet pipe 6 aforesaid.

20 are a series of delivery heads arranged near the top portion of the fire pot 2, and near the margin of the same as shown. Such delivery heads have discharge openings in their under sides so as to discharge the supply of heated air, furnished in manner herein-after described down upon the burning fuel to effect a very perfect combustion of the same.

21 is a header arranged exteriorly of the furnace casing 1, and having branch connections 22 with the series of delivery heads 20 aforesaid.

23 is a pipe arranged in right angle relation to the branch connections 22, and extending between the header 21 and the air heating space of the casing 10, and adapted to conduct a supply of heated air to such header.

24 is a valve arranged in the header 21 and adapted to control communication of the supply pipe 23 with the header, as well as communication of said header with the fur-

nace room, and thus enable the attainment of a very effective regulation of the quantity 65 as well as the temperature of the supply of air to the aforesaid delivery heads 20.

Having thus fully described my said invention what I claim as new and desire to secure by Letters Patent, is:—

1. In a hot air heating system, the combination of a hot air furnace having an air inlet and an outlet pipe for the products of combustion, of a preheating attachment arranged horizontally and formed with compartments in parallel relation and with one arranged within the other, the inner compartment having connection with the outlet pipe aforesaid by means of a pair of branch pipes connected to the respective ends of said compartment, a valve in said outlet pipe intermediate of said branch pipes to direct the products of combustion to the atmosphere or to the preheating attachment, the outer compartment having connection with the air 85 inlet aforesaid and adapted to preheat the supply of air to said inlet, a series of baffle plates arranged in the interior compartment and lateral passageways extending through the outer compartment from the inner compartment, substantially as set forth.

2. In a hot air heating system, the combination with a hot air furnace having an air inlet, a fire pot, a combustion chamber and an outlet pipe for the products of combustion, of a preheating attachment formed with separate compartments one of which is adapted to receive the products of combustion from said outlet pipe, and the other to receive the supply of air to said air inlet and preheat the same, a series of discharge heads arranged above the fire pot, and connections between said heads and the air heating compartment of the preheating attachment, substantially as set forth.

3. In a hot air heating system, the combination with a hot air furnace having an air inlet, a fire pot a combustion chamber and an outlet pipe for the products of combustion, of a preheating attachment formed with separate compartments one of which is adapted to receive the products of combustion from said outlet pipe, and the other to receive the supply of air to said air inlet and preheat the same, a series of discharge heads arranged above the fire pot, a valved header common to the series of discharge heads, and pipe connections between said heads, the header and the air heating compartment of the preheating attachment, substantially as 115 set forth.

4. In a hot air heating system, the combination with a hot air furnace having an air inlet, a fire pot, a combustion chamber and an outlet pipe for the products of combustion, of a preheating attachment formed

with separate compartments one of which is adapted to receive the products of combustion from said outlet pipe, and the other to receive the supply of air to said air inlet and 5 preheat the same, a series of discharge heads arranged above the fire pot, connections between said heads and the air heating compartment of the preheating attachment, and

an inclined deflector arranged in the combustion chamber, substantially as set forth. 10

Signed at St. Louis, Missouri, this 19th day of December, 1907.

ROBERT G. SPEER.
